J. H. DEAN.

FLOUR SIFTER.

APPLICATION FILED SEPT. 10, 1921.

1,401,142.

Patented Dec. 27, 1921.

UNITED STATES PATENT OFFICE.

JAMES H. DEAN, OF CHICAGO, ILLINOIS.

FLOUR-SIFTER.

1,401,142.

Specification of Letters Patent. Patented Dec. 27, 1921.

Application filed September 10, 1921. Serial No. 499,791.

To all whom it may concern:

Be it known that I, JAMES H. DEAN, a citizen of the United States, and a resident of Chicago, county of Cook, and State of Illinois, have invented certain new and useful Improvements in Flour-Sifters; and I do hereby declare that the following is a full, clear, and exact description thereof, reference being had to the accompanying drawings, and to the letters of reference marked thereon, which form a part of this specification.

This invention relates to improvements in flour sifters and consists of the matters hereinafter described and more particularly pointed out in the appended claims.

One of the objects of the present invention is to simplify the construction and to improve the operation of the sifter illustrated and described in my prior U. S. Letters Patent No. 1,369,700 issued on March 1, 1921.

Other objects of the invention as well as the many advantages thereof will more fully appear as I proceed with my specification.

25 In the drawings:—

Figure 1 is a view partly in elevation and partly in vertical section of a sifter embodying my invention;

Fig. 2 is a vertical section on the line 2—2
30 of Fig. 1;

Fig. 3 is a horizontal section through the sifter on the line 3—3 of Fig. 2;

Fig. 4 is a detail vertical section taken on the line 4—4 of Fig. 1;

35 Fig. 5 is a view in side elevation of a supporting bar embodied in my improved sifter and which will be more specifically referred to later;

Fig. 6 is a view in elevation of an actuator plate embodied in my improved sifter and which will be more specifically referred to later.

Referring now in detail to that embodiment of the invention illustrated in the accompanying drawing, 10 indicates the sifter casing as a whole. It includes a downwardly tapering top part 11 and a hopper-shaped bottom part 12 which are seamed together, there being an inwardly extending annular shoulder 13 at the junction of said parts. Both casing parts are circular in cross section. The bottom part 12 has a discharge spout 14 and the top part 11 has an outwardly extending stiffening bead 15 near its bottom end, and oppositely arranged, out-

wardly extending ears 16 by which the sifter casing as a whole may be detachably secured to the hopper bottom of a flour-bin (not shown).

Within the upper portion of the casing 10 is arranged a sieve or sifter basket 17, within which the bottom end of the hopper of the flour-bin extends, when the sifter is secured to the flour-bin. The sifter basket herein illustrated is substantially saucer-shaped. It is made of wire cloth and has a rolled sheet metal top rim 18.

19 indicates a diametric member which is fixed at its ends to the rim of the basket. Said member includes a cross bar or intermediate part 20 which supports and bows upwardly the central portion of the basket, and end loops or feet 21 which depend below said intermediate part and terminate in upwardly extending parts or legs 22. The top ends of the legs are secured to diametrically opposite points of the rim 18 of the basket.

The diametric member 19 is adapted to be removably engaged with a horizontally disposed oscillating flat bar 24 which is pivoted at its middle by a rivet 25 to the top end of a block or standard 26. This block is mounted on a transverse bar 27 supported in the casing 10 in a manner soon to appear. Preferably the rivet 25 which is arranged in the axial plane of the casing, has a driving fit in the block and a washer 25^a is interposed between the top surface of the bar 24 and the head of said rivet, to prevent binding of said bar. The ends 28 of the bar 24 are bent downwardly and have slots 29 therein so as to provide stirrups which receive the end loops or feet 21 of the diametric member 24. When the basket is in position upon the bar, the horizontal parts of the feet 21 rest in the bottom ends of the slots 29 with the shorter upright parts of said feet engaging in those parts of the slots in the ends of the bar 24 proper. Thus as it is apparent, when the bar 24 is oscillated, a like movement is imparted to the basket through the member 19 and an easy and quick removal and replacement of the basket is had with reference to said bar. It is herein pointed out that the basket is supported and has movement imparted to it from opposite sides as distinguished from those wherein the basket is supported at its center only. This construction is much stronger and it per-

mits of a two point engagement with the actuating mechanism so that the basket will always maintain its true shape.

The mechanism for oscillating the basket 5 is located in the casing below the basket and is mounted on the block or standard 26 before mentioned. Said mechanism includes a pair of vertically swinging, parallel spaced arms or links 30 which have top and bottom 10 tom horizontally disposed, opposite extensions 31—32. The extensions 31 are pivotally engaged in spaced transverse holes 33 in the top end of the block 26 while the extensions 32 are likewise engaged in similar holes 15 34 in the bottom end of an actuator plate 35. This plate extends parallel with the block 26 and is held in a position spaced therefrom by a boss 36 on the bottom end of said block, as clearly shown in Fig. 2. The top end of 20 the actuator plate is recessed at its middle as at 37 to provide spaced fingers 38 to engage opposite edges of the oscillatable bar 24. It is apparent that as the links are swung first in one direction and then in the other, an 25 oscillating movement is imparted to the actuator plate and consequently to the bar 24 and basket 17, the engagement of the fingers 38 with the bar 24 being so arranged that the bar actually limits the movement of the 30 plate for a purpose to appear later.

To impart the swinging or oscillating movement to the links 30 I provide a multi-pointed cam or star wheel 40 spaced outwardly a short distance from the actuator 35 plate and arranged in the plane of the extensions 32 of the links. As shown herein, said cam or star wheel is made integral with a shaft section 41 which has bearing in a hole 42 arranged centrally of the boss and in 40 a plane midway between and below the plane of the holes 33. In that end of the shaft section which projects beyond the opposite face of the block 26, is provided a recess 43 (see Fig. 2) and a cotter pin 44 extends through 45 this end of the shaft section to prevent endwise movement of said shaft section and star wheel. To assist in the proper spacing of the star wheel and shaft section, I interpose a washer 45 between the cotter and adjacent 50 face of the block and on said shaft section near the star wheel I provide a shoulder 46 which engages with the face of the boss 36. In the bottom edge of the actuator plate 35 I provide a downwardly opening recess 47 55 which straddles the shoulder 46. Preferably this recess is of such width that it is covered on one side at all times by the face of the boss, and the side walls of the recess are flared or tapered outwardly so that such 60 flour as enters the recess can not pack therein but will readily discharge itself therefrom.

The multipointed cam or star wheel has an odd number of points or teeth 48, preferably 65 five in number, and each point is substan-

tially heart-shaped so that diametrically opposite each point is a valley 49. It is apparent that as the cam is rotated the edge of one point or tooth on one side of the axis will engage with one of the link extensions 32 70 and swing it to one side, the other link entering into the diametrically opposite valley. After the highest part of the point has passed its associated extension, the approaching edge of the second point 48 spaced therefrom will engage the other extension 32 and swing the associated link in the opposite direction, the first-named extension moving into the approaching valley. It is herein pointed out that the edges of each tooth are 75 so generated that the swinging movement of the active link extension 32 is slowed down as it approaches the end of its limit of movement and that the other extension while entering the valley does not engage the body 80 of the cam but is free therefrom, as shown in Fig. 1. By reason of this construction and by reason of the limiting action of the fingers 38 of the actuator plate 35 with reference to the oscillating bar 24 as before described (the cam being made in synchrony therewith) the momentum of the basket is readily overcome, the cam does not become unduly worn or indented and the reversal is easily made without excessive jarring and 95 vibration.

The shaft extension 41 is driven or rotated by a shaft 50 which bears in a suitable plate 51 on the inside of the casing wall part 11. One end of said shaft is split as at 52 to 100 provide a fork which may be entered into the recess 43 of the shaft section 41 and to so straddle and engage the cotter 44 as to rotate the shaft section when the shaft 50 is rotated. That part of the shaft 50 without the casing 105 is formed to provide a crank 53 for rotating the same. To hold the shaft 50 in position with reference to the shaft section 41, I surround that part of the shaft within the casing with a coiled expansion spring 54 which 110 is interposed between the bearing plate 51 and a fixed washer 55 on said shaft near its forked end. The shaft 50 may be moved endwise outwardly against the spring 54 to remove it from engagement with the shaft 115 section 41. It is apparent that for every revolution of the shaft 50 five oscillations are imparted to the sifter basket.

The cross bar 27 which carries the block or standard 26 is removably mounted in the 120 casing in the following manner: The ends of the cross bar are tapered or inclined to correspond to the taper of the top part 11 of the casing. Said bar rests with the ends of its bottom edge upon the annular shoulder 125 13 and on opposite sides of the casing part 10 below the bead 15 are formed vertically arranged inwardly extending ribs 56 arranged in pairs. The ribs of each pair are spaced a distance apart substantially equal 130

to the thickness of the bar 27 so that said ribs engage the side portions of the ends of said bar to hold it in an edgewise manner. Just above the head 15 in a plane between 5 the ribs 56 of each pair, the metal of the casing part 11 is upset inwardly to provide lugs 57, which when the bar is in place, act to hold it from an upward movement. In applying or inserting the bar in place, one 10 end of said bar is arranged between one pair of ribs 56, with its topmost corner engaged beneath the associated lug 57. The other end of the bar is now guided into position between its associated pair of ribs and is forced 15 to pass the associated lug 57 by slightly springing the casing in a direction parallel with the bar. To remove the bar, the operations are in the inverse order.

My improved construction has many advantages, all of the operating mechanism may be assembled upon the block 26 before the bar 27 is inserted in place. The entire sifter may be readily taken apart and this without the necessity of removing such parts 25 as are liable to become lost. Flour cannot pack in or about the parts so as to slow down the sifting operations. The parts are simple and easy to make and assemble and thus an increase in production is attained with a corresponding reduction in the cost of manufacture.

While in describing my invention I have referred to certain details of mechanical construction, form and arrangement of parts, 35 I do not wish to be limited thereto except as is pointed out in the appended claims.

I claim as my invention:

1. A flour sifter comprising a sifter casing, 40 a sieve basket removable from said casing, a diametric member fixed at its ends to the top of the basket and having an intermediate part and end loops depending below said intermediate part, a bar mounted in the casing and capable of oscillation in a horizontal 45 plane about a point midway of its length, said bar having stirrups adapted to be engaged by said depending loop, and means for oscillating said bar.

2. A flour sifter comprising, a sifter casing, 50 a sieve basket in said casing having a dished wire cloth body and a metal rim, a diametric member fixed at its ends to the rim, said member including an intermediate part and parts depending below said intermediate part, and an oscillatable bar in said casing adapted for engagement by the end parts of said diametric member.

3. A flour sifter comprising, a sifter casing, 60 a sieve basket in said casing having a dished wire cloth body and a metal rim, a diametric member fixed at its ends to the rim, and means in said casing and adapted for engagement with said diametric member at points spaced from its middle for oscillating 65 said diametric member.

4. A flour sifter comprising, a sifter casing, a sieve basket in the casing having a rim, a diametric member for the sieve basket fixed at its ends to the rim, a horizontally disposed oscillatable bar pivoted between its 70 ends in the casing, said diametric member including parts adapted for detachable engagement with the oscillatable bar, and means in the casing for oscillating said bar.

5. A flour sifter comprising, a sifter casing, 75 a sieve basket in the casing having a rim, a diametric member for the sieve basket fixed at its ends to the rim, a horizontally disposed oscillatable bar pivoted between its ends in the casing, said bar having slotted 80 end parts adapted to be detachably engaged by parts of said diametric member, and means for oscillating said bar.

6. A flour sifter comprising, a sifter casing, 85 a sieve basket in the casing having a rim, a diametric member for the sieve basket, fixed at its ends to the rim, a horizontally disposed oscillatable bar pivoted between its ends in the casing, said bar having angularly disposed end parts with which 90 said diametric member has a detachable driving connection, and means for oscillating said bar.

7. A flour sifter comprising, a sifter casing, 95 a sieve basket in the casing having a rim, a diametric member for the sieve basket, fixed at its ends to the rim, a horizontally disposed oscillatable bar pivoted between its ends in the casing, said bar having downwardly extending slotted end parts 100 within which parts of the diametric member engage for a driving connection therewith, and means for oscillating said bar.

8. A flour sifter comprising, a sifter casing, 105 a sieve basket in the casing having a rim, a diametric member for the sieve basket, fixed at its ends to the rim, a horizontally disposed oscillatable bar pivoted between its ends in the casing, said bar being formed at its ends to provide stirrups and 110 said diametric member being formed to provide spaced feet which are adapted to engage in the stirrups, and means for oscillating the bar.

9. A flour sifter comprising a sifter casing, 115 a bar pivoted between its ends in said casing so as to oscillate in a horizontal plane, a sieve basket adapted for detachable engagement with said bar, a horizontal shaft rotatably mounted in the casing below said basket, an actuator plate mounted in the casing and capable of an oscillating movement in a plane at right angles to the shaft, said actuator plate being operatively connected with said bar, and means associated 120 with the shaft for oscillating said actuator plate.

10. A flour sifter comprising a sifter casing, 125 a bar pivoted between its ends in said casing so as to oscillate in a horizontal plane, 130

a sieve basket adapted for detachable engagement with said bar, a horizontal shaft rotatably mounted in the casing below said basket, an actuator plate mounted in the casing and capable of an oscillating movement in a plane at right angles to the shaft, said actuator plate having laterally spaced parts at its top end adapted to engage the edges of said bar so as to impart an oscillating movement thereto, and means associated with the shaft for oscillating said actuator plate.

11. A flour sifter comprising a sifter casing, a bar pivoted between its ends in said casing so as to oscillate in a horizontal plane, a sieve basket adapted for detachable engagement with said bar, a horizontal shaft rotatably mounted in the casing below said basket, an actuator plate mounted in the casing and capable of an oscillating movement in a plane at right angles to the shaft, said actuator plate having operative connection with said bar so as to impart its oscillating movement thereto, said connection being so arranged as to limit the amplitude of oscillation of said plate, and means associated with the shaft for oscillating said actuator plate.

12. A flour sifter comprising a sifter casing, a sieve basket mounted therein to oscillate about a central axis, a horizontal shaft section rotatably mounted in the casing below the sieve basket, an actuator plate mounted in the casing to oscillate in a plane at a right angle to the shaft section, a member for transmitting the oscillation of the actuator plate into a horizontal oscillation of the basket, means on one end of the shaft section for oscillating the actuator plate, and an operating shaft detachably connected to the other end of the shaft section.

13. A flour sifter comprising a sifter casing, a sieve basket mounted therein to oscillate about a vertical axis, a support in the casing below the basket, a horizontal shaft section journaled in the support, an actuator plate mounted on the support to oscillate in a plane at a right angle to the shaft section, a member for transmitting the oscillation of the actuator plate into a horizontal oscillation of the basket, means on one end of the shaft section for oscillating the actuator plate, a cotter passing through the other end of the shaft for locking said shaft section against endwise movement in one direction, and an operating shaft in line with the shaft section, the inner end of said shaft being forked and adapted to enter the recess in the end of the shaft section and engaging the cotter to provide a driving connection between the shaft and shaft section.

14. A flour sifter comprising a sifter casing, a sieve basket mounted therein to oscillate about a vertical axis, a support in the casing below the basket, a horizontal shaft section journaled in the support, an actuator plate mounted on the support to oscillate in a plane at a right angle to the shaft section, a member for transmitting the oscillation of the actuator plate into a horizontal oscillation of the basket, means on one end of the shaft section for oscillating the actuator plate, an operating shaft detachably connected to the other end of the shaft section, and a coiled spring on the shaft for holding it in engagement with the shaft section.

15. A flour sifter comprising a casing, a sieve basket mounted in the casing for oscillation in a horizontal plane, mechanism in the casing for imparting an oscillating movement to the sieve basket, and a support upon which said mechanism is mounted, said support being removably secured in said casing.

16. A flour sifter comprising a casing, a sieve basket mounted in the casing for oscillation in a horizontal plane, mechanism in the casing for imparting an oscillating movement to the sieve basket, and a support upon which said mechanism is mounted, said casing being constructed at diametrically opposite sides, to engage and removably hold said support in its proper position.

17. A flour sifter comprising a casing, a sieve basket mounted in the casing for oscillation in a vertical plane, mechanism in the casing for imparting an oscillating movement to the basket, a support in the casing below the basket and including a cross-bar and a block fixed thereon, said block carrying the mechanism for oscillating the basket, and means on opposite sides of the casing for receiving and removably holding the ends of said cross-bar.

18. A flour sifter comprising a sifter casing, a horizontally oscillatable basket in the casing, an operating mechanism in the casing for oscillating the basket, and means for detachably connecting the basket to said mechanism at points spaced from the axis of the basket, said means including parts for holding the basket upright and against lateral tipping.

In testimony that I claim the foregoing as my invention, I affix my signature in the presence of a witness, this 7th day of Sept., A. D. 1921.

JAMES H. DEAN.

Witness:

T. H. ALFREDS.
